(57) **CLAIM**

The ornamental design for a fire detector, as shown and described.

DESCRIPTION

FIG. 1 is a top perspective view of an inventive fire detector; FIG. 2 is a bottom perspective view of the fire detector depicted in FIG. 1;

FIG. 3 is a bottom view of the fire detector depicted in FIG. 1; FIG. 4 is a top view of the fire detector depicted in FIG. 1; and, FIG. 5 is a side view of the fire detector depicted in FIG. 1, where orthogonal side views and an opposing side view to that shown in FIG. 5 are identical that depicted in FIG. 5.
